UNITED STATES PATENT OFFICE

CHARLES B. HANOVER, OF SPOKANE, WASHINGTON

TOOTHBRUSH

Application filed January 16, 1928. Serial No. 247,101.

This invention relates to new and useful improvements in tooth brushes, and an object is to provide a sanitary tooth brush which may be manufactured at a very low cost so that after it has been used once or twice, it may, if desired, be thrown away and a new brush used the next time.

A further object of the invention is to provide a tooth brush constructed of a fibrous material such, for example, as wood or paper pulp, the brush comprising a body and handle integrally formed of sheet material, and the body having a plurality of fibrous protuberances of like material, suitably mounted

15 therein.

A further object is to provide a sanitary tooth brush comprising a body having a handle portion integrally formed therewith and suitably reinforced to prevent bending, and 20 the entire brush, including the protuberances being constructed of a fibrous material such as paper pulp.

The particular object of the invention therefore is to provide a sanitary brush constructed entirely of fibrous paper pulp material.

Other objects of the invention will appear from the following description and accompanying drawings and will be pointed out in 30 the annexed claims.

In the accompanying drawings, there has been disclosed a structure designed to carry out the various objects of the invention, but it is to be understood that the invention is 35 not confined to the exact features shown as various changes may be made within the scope of the claims which follow.

In the accompanying drawings forming 40 part of this specification;

Figure 1 is a perspective view showing the improved brush;

Figure 2 is a top plan view of the brush;

Figure 3 is a cross sectional view on the 45 line 3—3 of Figure 2, showing one method of securing the protuberances to the body;

Figure 4 is a cross sectional view on the line 4—4 of Figure 2, showing the means for reinforcing the handle;

50 Figure 5 is a view showing a modified form

of securing the protuberances to the body; and

Figure 6 is a modification showing another method of securing the protuberances to the brush body.

The novel brush featured in this invention comprises a body 2 having a handle portion 3 integrally formed therewith and preferably longitudinally recessed or ribbed as indicated at 4, to suitably reinforce the handle so that 55 it will withstand moderately rough usage.

A plurality of protuberances 5 are mounted in the body 2 and project outwardly therefrom as shown in Figure 1. In Figure 3, I have shown the protuberances made in the

form of staples and inserted through apertures provided in the brush body. The protuberances are preferably mounted in the brush body while the material from which the latter is made is in a moist condition, so that they may readily be inserted through the apertures provided therein, as shown in

Figure 3. The upper horizontal connections 6 of the protuberances may then be pressed into the upper surface of the body 2 to render the back of the brush comparatively 70 smooth when finished. I have found from actual experience that when the protuberances are thus mounted in the back 2, while the material from which the two parts are

75 constructed is still more or less moist, then when the brush is thoroughly dried, as when completed, the protuberances will be secured in the back so that they cannot accidentally become disengaged therefrom.

80 In Figure 4, I have shown the handle 3 longitudinally recessed in order to reinforce it. In the drawing, I have shown the handle recessed from the top or back of the brush, but it is to be understood, of course, that the handle may be recessed from the opposite side with equal results.

85 Figure 5 illustrates a modified form of securing the protuberances 7 to the back 2. As here shown, the material from which the protuberances are made is formed to provide folded-over portions or legs 8 which are adapted to be inserted into apertures provided in the brush back. A connection 9 connects together the portions 8 of the protuber- 90

ances. In the form here shown, the protuberances are inserted from the face or front side of the back 2, while in Figure 3, the protuberances are inserted into the body from the back thereof.

5 Figure 6 illustrates another method of mounting the protuberances in the body 2. In the form here shown, the protuberances are in the form of tapered points driven into the body 2 from the back of the brush.

10 The important feature in this invention, as before stated, is to provide a brush constructed entirely of paper pulp or a similar fibrous material. The brush is preferably constructed of fibrous sheet material which may be conveniently shaped and formed by suitable dies and punches so that the brush may be manufactured at a very low cost. I have also found that the protuberances may be manufactured 15 and mounted in the body 2 of the brush in a manner which will permit the entire brush to be manufactured at a cost sufficiently low to permit it to be thrown away each time it has been used, and a new one substituted 20 therefor each time the teeth are cleaned.

25 The construction of the brush is such that it may conveniently be packed and sealed in individual air-tight cartons and dispensed in vending machines located in such places as hospitals, hotels, schools, trains, and various other places. The brushes are thus sealed in individual sealed cartons, the user may be assured that they will be absolutely sanitary and sterile, thus substantially eliminating all 30 danger of mouth infection, often caused by using ordinary tooth brushes having hair bristles.

35 The paper or fiber tooth brush featured in this invention is primarily designed to be used but once, and will therefore be sterile before usage. After each using, it may be discarded and a new one used the next time, thus preventing the carrying of more bacteria into the mouth each time the teeth are brushed 40 or cleaned. It is becoming well known among authorities on this subject that the use of the ordinary tooth brush does not prevent the spread of disease and germs in the mouth, but rather tends to increase the spreading of the 45 bacteria.

50 The material from which this novel tooth brush is constructed is of such consistency that the protuberances or bristles will not soften in the mouth with the average amount 55 of use necessary for one cleaning so that, if desired, the brush may be used two or three times, after which it should be discarded and a new brush used the next time. It is desirable, however, that the brush be used only once, 60 thereby avoiding the possibility of bacteria being carried into the mouth with the previously used brush, as it is known often results when a brush is used a second or third time, because of the fact that it is practically 65 impossible to render an ordinary bristle

brush absolutely sterile, after it has once been used.

70 The type of tooth brush now commonly used is of such material that it cannot be thoroughly sterilized after usage without injuring the bristles and the supporting means therefor. Because the sanitary brush featured in this invention is used but once, or possibly twice, and then discarded, it, of course, does not need to be sterilized and, as 75 a result of a new brush being used each time the teeth are cleaned, the spreading of germs and disease in the mouth, which now often results from the use of the ordinary tooth brush, is practically prevented.

80 In the drawings, it will also be noted that the design of this novel brush is very similar to that of an ordinary tooth brush. It is to be understood, however, that the general design of the brush, including the protuberances may be varied in any manner desired 85 without departing from the scope of the invention.

I claim as my invention:

1. A tooth brush comprising a body portion and a handle portion integrally formed of fibrous sheet material, protuberances of fibrous material secured in said body portion, and a longitudinally extending rib in said handle portion to strengthen the same against 95 lateral pressure.

2. A toothbrush comprising a body portion and a handle formed integral therewith, both the body portion and handle composed of a fibrous material, and the body portion provided with openings therethrough in which bristle-projections of fibrous material are fitted.

In witness whereof, I have hereunto set my hand this 14th day of January, 1928.

CHARLES B. HANOVER.
